UNITED STATES PATENT OFFICE.

HERBERT A. BULLARD, OF SAN FRANCISCO, CALIFORNIA, ASSIGNOR TO INTERCONTINENTAL COMPANY, A CORPORATION OF CALIFORNIA.

CENTRIFUGAL GUN.

1,311,492.

Specification of Letters Patent. Patented July 29, 1919.

Application filed August 5, 1916. Serial No. 113,345.

To all whom it may concern:

Be it known that I, HERBERT A. BULLARD, a citizen of the United States, residing in San Francisco, California, have invented 5 certain new and useful Improvements in Centrifugal Guns, of which the following is a specification.

This invention aims to provide certain improvements in guns of this sort and in projectiles therefor having certain points of advantage referred to in detail hereinafter.

The accompanying drawings illustrate embodiments of the invention.

Figure 1 is a plan of a gun;

15 Fig. 2 is a side elevation thereof;

Fig. 3 is a cross-section thereof approximately on the line 3—3 of Fig. 1;

Figs. 4 and 5 are respectively a plan and a vertical section of the magazine;

20 Fig. 6 is a horizontal section of the barrel plate or projecting device with the feeding device or firing plate in plan;

Figs. 7 and 8 are sections of the barrel plate on the corresponding lines in Fig. 6;

25 Fig. 9 is a side elevation of an assemblage of disks cemented together;

Fig. 10 is a sectional view of a similar assemblage of disks fastened together by a central wire;

30 Fig. 11 is an elevation of a similar assemblage of disks carried in a casing which is shown in section;

Fig. 12 is a sectional view of a variant of the disks shown in the other figures.

35 Fig. 13 is a side elevation of a magazine latch;

Figs. 14 and 15 are plans of projectiles arranged in a continuous strip;

40 Fig. 16 is a central vertical section of a modified style of gun embodying the invention.

The gun is designed to take a projectile in the form of a disk and to project it at a high velocity, at the same time spinning it rapidly about its axis, which is arranged in a generally vertical position. The spinning produces a gyroscopic effect which maintains the disk in its plane throughout a long flight. The projectiles are placed in a magazine from the bottom of which they are taken one by one and fed into a rapidly rotating projecting member provided with one or more "barrels".

The feeding member or device may operate once as each barrel makes a complete rotation so that the number of feeding operations per second will equal the number of rotations of the projecting member multiplied by the number of barrels carried thereby. There is a limit to the speed of the feeding device, however, beyond which it becomes less reliable. Where there is one feeding operation for each rotation of a barrel, therefore, the limit on the feed puts a corresponding limit on the rate of rotation of the projecting member and requires it to be of comparatively large diameter in order to secure a high linear speed at the muzzle or point where the projectile leaves the projecting member. One of the features of advantage of my present invention is in the rotation of the projecting member faster than one revolution of each barrel for its feeding operation; thus permitting, for a given linear velocity at the muzzle, a projecting member of smaller diameter and a lighter and more compact gun.

Referring now to the embodiments of the invention illustrated, the projecting member indicated as a whole at A is formed of a single integral piece of steel, but it may be laminated or otherwise made of more than a single piece. For perfect balance it is provided with two (or it may be more than two) barrels B each having a concave lateral open groove C on its forward side to accommodate a projectile D. The center of the projecting member is formed with a circular opening to receive the "firing plate" or feeding plate E (Fig. 6). The central portion of the projecting member is also provided with a groove partly of uniform width as shown at F (Fig. 7) and partly tapered as shown at G, the latter portion communicating with the bore or groove C of the barrel. As the projecting member or barrel plate rotates a projectile is forced outward by the firing plate at a rate calculated to carry it into the groove C of the barrel at the inner end H thereof. The projectile rolls on the rear face of the groove C so as to be spun rapidly and is finally thrown from the muzzle or end of this groove at a high linear speed and with a high spinning rotation.

The barrel plate and feed plate are carried

95

100

105

- in a fixed casing comprising a top plate J, a bottom plate K and a ring L, the latter being broken away for a portion of its length as indicated in Fig. 1 at the point where the 5 projectiles are thrown from the end of the barrel B.
- The magazine comprises a vertical tube M, the lower end of which, in firing position, extends down to or nearly to the feeding or 10 firing plate E. The bottom and the lower portion of the sides of the magazine are slotted as shown in Figs. 3, 4 and 5. The plate E carries upward projections N which, as the plate rotates, pass through the slots 15 in the bottom of the magazine and force out the lowermost one of the projectiles D therein. Just beyond the position of the magazine there is a fixed guiding plate or block O provided on its underside with downward 20 ribs P between which the upward ribs N on the firing plate E pass, as shown in Fig. 6. As the firing plate and the ribs or lugs N advance they force the projectile D forward against the ribs P on the guiding plate 25 and cam the projectile approximately radially outward into the groove C of the barrel as above explained.

The guiding block O and the magazine M are both mounted in a plate or block Q (Fig. 3) rabbeted on its upper edge and on which is fastened a plate R which overhangs so as to form a groove into which enters a fastening plate S screwing onto the hub of the upper plate J of the fixed casing and 35 provided with handles T so that, when unscrewed, it can be lifted with the magazine and connected parts and removed to a place of safety, thus putting the gun out of use.

The lower plate K of the fixed casing is 40 provided with a tubular portion U inclosing certain gearing hereinafter referred to, to which tubular portion is attached a bottom plate V through which passes the driving shaft W. The fixed casing is mounted in 45 any suitable support such for example as that indicated at X, in Fig. 2, carrying a motor Y for driving the shaft. The shaft W has a reduced upper portion W' on which is rotatably mounted a hub Z which is keyed 50 to a base plate 2 fastened as by bolts 3 to the barrel plate. The upper end of the shaft is still further reduced as at W² and carries the feeding plate E so as to rotate the latter directly.

55 In order to rotate the barrel plate at a higher rate of speed it is driven by gearing from the shaft W. A spider 4 keyed on the lower portion of the shaft carries differential pinions 5 which engage teeth on the 60 lower portion of the hub or central gear Z and which also engage the internal teeth of a gear 6 which is normally fixed in position within the tubular portion U of the casing. The upper portion of the hub Z being fastened to the barrel plate, the latter will ro-

tate at a rate faster than that of the shaft and feeding plate and in proportion to the ratio of the gearing.

If the rotation of the firing plate and that of the feeding plate be commensurate, that is if the feeding plate rotate once for each one, two, three or more complete rotations of the firing plate, the projectiles will be fed always to the same barrel. And if a single barrel be used some such commensurate ratio will be necessary. But it is preferable, in order to secure a perfectly balanced barrel plate to have two or more barrels; even then we may use the commensurate rates of revolution, using a single 75 barrel until it is worn out, and may then adjust the parts to use another barrel. But it is preferably to set the machine to use first one barrel and then another so that they shall all be used equally and shall wear out 80 at the same time. I have, therefore, adopted a gearing which will bring different barrels into operation successively. For example, in the illustration the internal gear 6 has its pitch line two and a half times the length 85 of that of the external gear Z. This will give a speed of rotation of the gear Z and the barrel plate three and a half times that of the shaft and the feeding plate. Thus, for each operation there will be a movement 90 of the barrel plate relative to the feeding plate equal to three and a half revolutions, and this will bring the opposite barrel into operative position to receive the next projectile fed. The two barrels will, therefore, 95 operate alternately and will wear equally. Any number of revolutions plus a half will secure this result where the projecting member has two barrels. The rate of feed and the muzzle velocity being determined, the 100 projecting member or barrel plate may be of any desired diameter by correspondingly designing the gearing. For a gun having three barrels the relative speeds would be any whole number plus or minus one-third, 105 for a gun having four barrels it would be any whole number plus or minus one-fourth, 110 and so on.

The entire gun may be mounted in any suitable arrangement of trunnions or other 115 bearings for securing a greater or less elevation and for aiming to right or left. But we prefer for aiming to the right or to the left, the casing being fixed, to vary the angular position of the barrel with respect to 120 the fixed casing at the time a projectile leaves the muzzle. This result is secured by varying the angular position of the barrel at the time when the projectile is received at its inner end, the point H 125 in Fig. 6. This involves a similar adjustment of the angular position of the firing plate, since there is always the same interval of time between the ejecting of a projectile out of the magazine and the receiv- 130

ing of it on the inner end of the barrel. To fire more to the right the barrels therefore must be farther back than the position shown in Fig. 1 when they receive the projectile. The projectile is fed outward in a substantially radial direction by reason of the guides P. The adjustment for aim will always be so slight that the projectile D will be ejected from the magazine at a point 5 more or less to the rear of the radial line through the point H. If, however, the point H be adjusted to the left or forward say one millimeter the projectile D will be fed at a slightly delayed point and will be thrown 10 out into the projecting barrel C one millimeter later in the revolution of the barrel. With the two-barrel plate illustrated the projectile will be fired from the barrel opposite that toward which it is first fed into 15 the groove G, but the principle is the same 20 whether one or more barrels be used.

The aiming adjustment is effected by means of an arm 7 on a ring 8, the ring carrying a forward sight 9 and the arm a rear sight 10. The ring 8 is ordinarily clamped 25 to the fixed block 2 by means of a bolt 11 having a handle 12, the bolt passing through a slot 13 in the ring 8. When the bolt is clamped the aim is fixed. When the aim is 30 to be changed the parts are first unclamped and afterward clamped again. The arm 7 above the casing is connected at its outer end to a parallel arm 14 below the casing and at their outer ends these two arms carry 35 a shaft 15 on which is a pinion 16 mounted in a casing 17 in which is rotatably carried a worm 18 engaging the pinion 16 and rotated by a handle 19. The pinion 16 also engages teeth 20 formed in the ring L and constituting a rack, so that as the handle 19 is turned the arms 7 and 14 are carried 40 around the casing slowly. The arm 14 passes through a slot in the tubular portion U of the fixed casing and is fastened as 45 shown in Fig. 3 to the internal gear 6. When the aiming arms 7 and 14 are clamped fast the internal gear 6 is fixed. When these arms are unclamped, however, and are rotated around the casing the internal gear 50 6 is turned with them. Supposing the central shaft and the feeding plate E fixed, the adjustment of the internal gear to the right causes a movement of the hub Z and the barrel plate to the left. When the motor is in 55 operation, or in fact when the gun is firing the same adjustment of the aim may be made and there will be the same relative movement of the barrel plate to the magazine and feeding plate.

60 The magazine M is trunnioned as shown in Figs. 1 and 2 in an arm 21 pivoted to an upright on the plate R and carrying at its end a button 22 and at an intermediate point an adjustable stop pin 23, the lower 65 end of which bears on the ring 8. The plate

or block Q is shaped as shown in Fig. 5 with a depending portion embracing the magazine and formed with slots 24 into which enter springs 25 fastened to the magazine and tending to lift it clear of the firing position. Springs 26, which constitute preferably extensions of the springs 25, pass through the wall of the magazine and catch and hold the lowest projectile in its advanced position against any upward tendency due to the vibration of the machine or to the striking of the lowest disk by the feeding device. These springs, however, are so light that the weight of a few projectiles will be sufficient to cause them to yield and 70 permit the lowest projectile to pass below the end of the springs and on to the bottom of the magazine. The springs 25 are sufficiently strong to hold up the magazine so that the projections N of the feed plate will 75 pass below it. When the machine is speeded up and firing is to be commenced the operator has simply to press the button 22, thus forcing the magazine down to operative position. When the foremost projectile is fired 80 an appreciable interval will be required for the feeding of the next by gravity past the retaining springs 26. The projecting member, however, may make several revolutions before the projections N on the feed plate 85 will again come into action, and this will give sufficient time for a comparatively slow feed of the projectiles through the magazine. The feed may be assisted, if desired, 90 by placing a weight on top of the projectiles 100 in the magazine, such as is indicated at 27 (Fig. 2), with a head 28 which will strike the top of the magazine and so stop the movement of the weight when the last projectile has been forced to the firing point; 105 or any equivalent spring arrangement may be used to assist the feed. To avoid the necessity of the operator's holding the button 22 a latch 29 (Fig. 13) is mounted on the plate R and arranged to engage the side of 110 the lever 21 so as to hold the latter down after it has been pressed down by the button 22. To stop firing the operator has only to release the latch 29, whereupon the springs 25 will lift the magazine and hold 115 it in the inoperative position. To provide for continuous firing he has only to press the button 22 until the lever is caught by the latch 29 and held down.

120 For greater convenience and speed in handling the projectiles I prefer to assemble a number of them and unite them by a breakable connection. Examples of such assemblages of disks are illustrated in Figs. 9, 10 and 11. The disks are arranged face to 125 face in a stack of any desired number. In Fig. 9 they are united by an extremely thin layer of paraffin or other adhesive cementing material between each two disks. In Fig. 10 the disks are perforated and strung on a 130

pin or wire 30 of lead, solder or the like. In Fig. 11 they are embraced and held together by a casing or jacket 31 of cardboard, paper or the like. The blow of the feeding device 5 is sufficient in each case to separate the lowest projectile from those above it.

This provision of a breakable connection is useful whether the disks are passed through the magazine face to face, moving along an 10 axial line as indicated, or whether they are assembled edge to edge and passed along in an edgewise direction. In the latter case the same advantages would be secured by advancing them in the form of a continuous 15 strip from which the disks are cut or punched in succession and moved to position for engagement by the feeding plate as described. Two such strips are shown in Figs. 14 and 15 respectively. In Fig. 14 the disks 20 D are cut out around nearly their entire circumference, leaving only a small connecting piece of metal, and a slight blow is sufficient to break off the end disks. In Fig. 15 the disks D, indicated in dotted lines, are punched in succession from a straight-edged 25 strip of metal.

The edges of the projectile may be knurled or serrated so as to secure a better grip against the rear face of the groove of the 30 barrel so as to secure a better spinning effect. A similar result may be achieved by making the disks of soft metal on their edges (or throughout their extent). The barrel will preferably be of hardened steel, 35 which will take a good grip on the soft edges of such disks. This combination of a hard barrel and a soft-edged disk has also the advantage of reducing the wear on the barrel and increasing its life. An increased gyroscopic effect may be obtained by disposing 40 the greater quantity of metal in the disk near its outer edge, as for example in Fig. 12 where the disk D is shown with a comparatively thin central portion 32, which may 45 be perforated at the center or may be imperforate, and with a thickened rim portion 33.

An alternative arrangement is shown in Fig. 16 which permits the removal of the 50 feeding plate with the magazine. In this case the barrel plate A constitutes or is mounted on the upper end of the driving shaft W. A second shaft 34 carries a pin 35, the ends of which engage slots 36 in the hub 55 of the barrel plate; so that the shaft 34 is rotated with such hub but may be lifted out of engagement therewith. The shaft 34 carries a central pinion 37 engaging planetary pinions 38 carried on pins 39 which connect 60 the feeding plate E with a shell 40. The shell 40 has a rotative engagement with a tube 41 fastened to the fixed guide block O, the tube 41 having at its lower end an internal gear 42 in engagement with the planetary pinions 38. Now as the barrel plate A

and small shaft 34 are rotated, the external gear being held stationary, the small pinion 34 drives the planetary pinions 38 and causes a rotation of the feeding plate at the desired rate. When the plate N is unscrewed and 70 lifted by means of the handles T it will carry not only the magazine M and guide block O but also the feed plate and the planetary gearing, the lower end of the shaft 34 lifting freely out of engagement with the hub of the barrel plate. For aiming with 75 this construction it is only necessary to swing the arm 7 to the right or to the left by means of the handle thereon. This will turn the fixed block Q and the magazine relative 80 to the feeding and projecting plates and will thus cause the projectile to be fed and projected earlier or later in the revolution of the barrels.

Though I have described with great particularity of detail certain specific embodiments of my invention yet it is not to be understood therefrom that the invention is restricted to the embodiments illustrated. Various modifications thereof in detail and 90 in the arrangement of the parts may be made by those skilled in the art without departing from the invention.

What I claim is—

1. A centrifugal gun for firing disk-shaped projectiles and giving them a spinning motion comprising a rotating projecting member and a rotating feeding member, the projecting member having a plurality of barrels and rotating faster than the feeding member and at a rate to bring different barrels into operation successively. 95

2. A centrifugal gun for firing disk-shaped projectiles and giving them a spinning motion comprising a rotating projecting member, a feeding member, a magazine carrying a number of projectiles, said magazine and the feeding member being one movable relatively to the other. 105

3. A centrifugal gun for firing disk-shaped projectiles and giving them a spinning motion comprising a rotating projecting member, a feeding member, a magazine carrying a number of projectiles and movable to operative position for engagement of the projectiles by said feeding member or to inoperative position and means for holding it in either position to which it may be moved. 110

4. A centrifugal gun for firing disk-shaped projectiles and giving them a spinning motion comprising a rotating projecting member, a feeding member, a magazine carrying a number of projectiles and movable to operative position for engagement of the projectiles by said feeding member or to inoperative position, means for locking it in operative position and a spring pressing it toward inoperative position. 115

5. A centrifugal gun for firing disk- 120

- shaped projectiles and giving them a spinning motion comprising a rotating projecting member, a feeding member, a magazine carrying a number of projectiles and movable to operative position for engagement of the projectiles by said feeding member or to inoperative position and means for engaging the most advanced projectile in the magazine and holding it against backward movement.
6. A centrifugal gun for firing disk-shaped projectiles and giving them a spinning motion comprising a rotating projecting member and a rotating feeding member, the projecting member rotating faster than the feeding member and means for adjusting the aim of the gun by turning the projecting member and the feeding member through distances which are in the ratio of their speeds of operation.
7. A centrifugal gun for firing disk-shaped projectiles and giving them a spinning motion comprising a rotating projecting member of comparatively hard metal in combination with disks of comparatively soft metal adapted to be spun and projected by the engagement of said member with the edges of the disks.
8. A centrifugal gun for firing disk-shaped projectiles and giving them a spinning motion including a one-piece barrel plate having a laterally open firing groove.
9. A centrifugal gun for firing disk-shaped projectiles and giving them a spinning motion including a one-piece barrel plate having a laterally open firing groove in one side edge and having a central annular groove for receiving a projectile and guiding it into said firing groove.
10. A centrifugal gun for firing disk-shaped projectiles and giving them a spinning motion including a rotating barrel plate, a rotating feeding plate for feeding projectiles and a fixed guiding plate for guiding such projectiles to the barrel plate.

In witness whereof, I have hereunto signed my name.

HERBERT A. BULLARD.
